CHAMFERING TOOL

Don Heyer, Los Angeles, Calif.

Application October 14, 1942, Serial No. 461,966

20 Claims. (Cl. 77—73)

This invention relates to metal working tools, and more particularly to tools for finishing, chamfering, counter-sinking and spot facing in conjunction with bored, drilled or reamed holes.

The production of holes through metal or analogous substances usually results in sharp corners or even projecting edges which are commonly referred to as burrs. When milling a surface which extends across a bore the milling cutter produces sharp edges or burrs at the junction between the walls of the bore and the finished surface produced. It is common practice to require that the sharp edges or burrs in metal be removed regardless of how they are produced. In the past this has been done by the use of a file or scraper, or by means of grinding.

There are several situations in which the conventional tools for breaking the edge or removing the burr around an opening will not satisfy. When a drilled, reamed, or bored hole extends completely through a metal structure removal of the burrs from both ends of the bore is usually desirable. Oftentimes it is also desirable to spot-face the surface adjacent each end of the hole. The exigencies of design, such as multiple-walled parts where several aligned holes are drilled or reamed through closely spaced walls, oftentimes leaves insufficient room for easy removal of the burr on all the surfaces of the work.

It is an object of the present invention to provide a tool for spot-facing, counter-sinking, or chamfering having a cutter that can be readily inserted through a bore and projected during rotation of the tool to perform the operation.

It is another object of the invention to prevent the inadvertent projection of the blade during its passage through the bore.

A further object of the invention is the provision of means for positively holding the blade in operative position.

It is an object of the present invention to provide a device for spot-facing, counter-sinking or chamfering, which can be readily passed through a bore and operated at either end thereof to perform the finishing operation.

It is an object of the present invention to provide a device which may be readily incorporated in a boring, drilling or reaming tool, and which will be adapted to the counter-sinking, chamfering or spot-facing of the work being operated upon.

It is a further object of the present invention to provide a device for spot-facing, chamfering, or counter-sinking in which the cutting element can be readily removed from the holder.

It is a further object of the present invention to provide a spot-facing, counter-sinking or chamfering tool which normally does not interfere with the reaming operation.

This invention possesses many other advantages and has other objects which may be made more easily apparent from a consideration of one embodiment of the invention. For this purpose there is shown a form in the drawing accompanying and forming part of the present specification. This form will now be described in detail, illustrating the general principles of the invention; but it is to be understood that this detailed description is not to be taken in a limiting sense, since the scope of the invention is best defined by the appended claims.

Referring to the drawing:

Figure 1 is a view partly in section, showing one form of the present invention in which the 20 chamfering device is incorporated in a reamer;

Figure 2 is a transverse section taken along line 2—2 of Figure 1; and

Figure 3 is a transverse section taken along line 3—3 of Figure 1.

Referring in particular to Figure 1, an elongated body member 10 is provided with reamer blades 11 at one end and a shank portion 12 at the opposite end by which the tool may be held in a chuck or the like and rotated, or stationarily held while the work is revolved. Within the body 10 there is provided an elongated slot 13. This slot is shown as having a bottom which is curved at both ends as at 14 and 15 for purposes which will presently appear. An elongated cutter element 16 is slidably contained in the slot 13 and carries on one end thereof a cutting blade 17. This cutting blade 17 may be provided with cutting edges of any form desired depending upon the function to be performed by it. In the shown form, the cutting blade 17 is intended for chamfering the ends of the bores reamed by the reaming blades 11. As it is desired to chamfer both the top and bottom of the holes produced, the blade 17 has its edge 18 and its edge 18' suitably formed to perform this function. It can be readily seen that if the blade 17 is in the projected position shown in light broken lines, Figure 1, it will chamfer the edge of a hole when the entire tool is moved axially in either direction.

As it is desired to be able to chamfer the bottom edge of a hole reamed by the reamer 11, it is necessary that the cutting blade 17 be retractable from the projected position shown in light broken lines. In order to retract the tool, 55 and at the same time permit its positive support

in the projected position, the structure shown on the right hand end of Figure 1 is employed. This structure comprises a collar 19 mounted on the elongated body 10 for sliding movement longitudinally thereof. The interior of the collar is provided with a slot 20 which is in alignment with the slot 13 in the body 10 and receives the end of the elongated cutter element 16 opposite the end upon which the blade 17 is mounted. The entire cutter element 16 cooperates with the curved bottom portions of the slot 13 and with the collar 19 in such a manner that movement of the collar axially of the body 10 will result in projection and retraction of the blade 17 in a positive manner.

As can be seen in Figure 1, the cutter element 16 is curved at 15a to substantially fit the bottom curve 15 of the slot 13. A pivot pin 22 in the collar 19 extends through the slot 20 of the collar and engages a notch 23 in the upwardly extending portion 24 of the cutter element 16. The end of the cutter element 16 is yieldingly held against the pivot pin 22 by a spring mounted on the collar 19. This spring is shown as being of a more or less circular configuration, having one end secured to the collar by a pin 27 and the other end engaging a notch 28 in the underside of the cutter element 16 to one side of the pivot pin.

The cooperation between the pivot pin 22, the shape of the bottom of the cutter element 16, and the shape of the slot 13 is such, that reciprocation of the collar 19 on the body 10 results in the projection and retraction of the blade 17. Thus, when the collar 19 is moved to the left from the solid line position, Figure 1, the blade carrying end of the cutter element 16 slides over the curved portion 14 of the slot 13, causing a projection of the blade beyond the outer surface of the elongated member 10. The projection of the blade 17 is limited by the engagement of the collar 19 with an abutment ring 30 on the elongated body 10. The limit of the projection can be varied by adjusting the abutment ring longitudinally of the body 10, which is made possible by the set screw 31. It can be seen, that when the blade 17 is in the projected position shown in light broken lines, a portion of the cutter element 16 beneath the blade bears against the curved portion 14 of the slot 13, thereby rigidly supporting the blade during the cutting operation on the work.

When the collar is moved back to the right, the reengagement of the curved portion 15a of the cutter element 16 with the curved portion 15 of the bottom of the slot 13, causes a positive retraction of the blade 17. This can be more readily appreciated by considering the fact that a normal drawn from the center of the pin 22 to the curved portion 15 of the slot 13 is the shortest distance from that center to the bottom of the slot 13. The engagement of the bottom of the slot and the corresponding surface of the cutter element 16 to the right of the point where the normal meets the curve bottom tends to turn the element 16 about the pin 22 in a counter-clockwise direction. Thus it is impossible for centrifugal force to lift the cutter element 16 and blade 17 out of the position shown in solid lines in Figure 1.

The spring 25 cooperates with the pin 22 to perform all the functions of holding the cutter element 16 and its blade in place in the assembly. In addition to this, it serves the important function of preventing the cutter element 16 from flying outwardly under the influence of centrifugal force during movement of said element between its two extreme positions of adjustment. For instance, when the collar 19 is moved to the

left from the solid line position in Figure 1, the engagement between the curved portion 15 of the bottom of the slot 13 and the corresponding curved portion 15a of the cutter element 16 is broken. Thus, the blade 17 would be free to move outwardly under the influence of centrifugal force but for the spring 25, which is of sufficient strength to prevent such movement. The use of a spring 25 also permits ready removal of the cutter element 16 for sharpening the blade 17 or for replacement. It is merely necessary to move the collar 19 to a position to the left of that shown in Figure 1 in solid lines, and press downwardly upon the free end of the spring 25 to release the entire element from the influence of the spring and the pin 22. The cutter element 16 can then be slid out from the slot in the collar and removed.

Inasmuch as the collar 19 is intended to be reciprocated while the tool is in motion it is desirable to provide a second collar 33 surrounding the collar 19. This second collar 33 is mounted for rotation with respect to the collar 19 by means of the balls 34 running in races in the two collars. This outer collar 33 may be safely grasped in the hand of the operator during rotation of the tool in order to produce the axial movement of the collar 19 for projection or retraction of the blade 17.

As it is desired to prevent the blade 17 from moving outwardly into engagement with the walls of a bore during its passage therethrough, the collar 19 is provided with a snap catch to hold it in the position shown in solid lines. This snap catch can be in the form of a small ball 36 which is forced into a depression 35 in the member 10 by a spring 37 contained within a bore in the collar 19. This snap catch positively holds the collar 19 and cutter element 16 in retracted position. It can be seen that so long as the ball 36 is in the depression 35 it is impossible for the blade 17 to move outwardly and mar the work, because of the engagement of the bottom of the cutter element 16 with the curved portion 15 of the bottom of the slot 13. If desired, a second depression 38 may be provided in the elongated member 10 to receive the ball 36 and positively hold the collar 19 and the cutter element 16 in projected position.

I claim:

1. A tool for chamfering and the like comprising, a body adapted for insertion through a bore, a cutting blade mounted on said body for movement between a position shielded within the body and a cutting position exterior of the body, means including a member freely rotatably with respect to the body, said member being adapted to move said blade between said positions during rotation of said tool, and means locking said blade in at least one of said positions.

2. A tool for chamfering and the like comprising, a body adapted for insertion through a bore, said body having a slot therein, a surface of said slot having portions oppositely inclined with respect to the axis of the body, a cutter element having a blade adapted to be shielded within said slot, and means causing relative movement between said cutter element and said inclined surfaces to project said blade from the slot or to retract the blade within the slot in accordance with the direction of movement.

3. A tool for chamfering and the like comprising, a body adapted for insertion through a bore, said body having a slot therein, a surface of said slot having portions oppositely inclined with re-

spect to the axis of the body, a cutter element having a blade adapted to be shielded within said slot, means causing relative movement between said cutter element and said inclined surfaces to project said blade from the slot or to retract the blade within the slot in accordance with the direction of movement, and means positively holding said cutter element in shielded position.

4. A tool for chamfering and the like comprising, a body adapted for insertion through a bore, said body having a slot therein, a surface of said slot being inclined with respect to the axis of the body, a cutter element having a blade shielded within said slot, said cutter element having a portion engageable with said inclined surface to project the blade from the slot, and means moving said blade into retracted position within said slot upon movement of said cutter element out of engagement with said inclined surface.

5. A tool for chamfering and the like comprising, a body adapted for insertion through a bore, said body having a slot therein, a surface of said slot having axially spaced portions oppositely inclined with respect to the axis of the body, a cutter element having a blade, and means causing relative movement between said cutter element and said inclined surfaces, movement in one direction serving to project said blade from the slot, one of said surfaces positively supporting said blade in projected position, movement in the opposite direction serving to retract the blade within the slot, the other surface cooperating with said means to positively maintain the blade in retracted position.

6. A tool for chamfering and the like comprising, an elongated body adapted for insertion through a bore, a member mounted on said body for relative axial movement with respect thereto, a cutter element pivotally mounted on said member and having a blade shielded within said body, and means on said body cooperating with said cutter element to move said blade from a shielded to a cutting position upon relative axial movement between said member and said elongated body.

7. A tool for chamfering and the like comprising, an elongated body adapted for insertion through a bore, said body having a slot therein, a member mounted on said body for relative axial movement with respect thereto, a cutter element pivotally mounted on said member and having a blade shielded within the slot, and means in said slot projecting said blade from the slot upon relative axial movement between said elongated body and said member.

8. A tool for chamfering and the like comprising an elongated body adapted for insertion through a bore, said body having a slot therein, a surface of said slot being inclined with respect to the axis of the body, a member mounted on said body for relative axial movement with respect thereto, a cutter element pivotally mounted on said member and having a blade shielded within the slot, said cutter element having a portion engageable with the inclined surface of said slot to project the blade from the slot upon relative axial movement between said member and said elongated body, said inclined surface positively supporting the blade in said projected position.

9. A tool for chamfering and the like comprising an elongated body adapted for insertion through a bore, said body having a slot therein, a surface of said slot being inclined with respect

5 to the axis of the body, a member mounted on said body for relative axial movement with respect thereto, a cutter element pivotally mounted on said member and having a blade shielded within the slot, said cutter element having a surface on one side of its pivot engageable with the inclined surface of the slot to project the blade therefrom upon movement of the member, and means on the elongated body positively retracting the blade into the slot upon movement of the member in the opposite direction.

10. A tool for chamfering and the like comprising an elongated body adapted for insertion through a bore, said body having a slot therein, the ends of said slot having surfaces inclined with respect to the axis of the body, a member mounted on said body for relative axial movement with respect thereto, a cutter element pivotally mounted on said member and having a blade shielded within the slot, said cutter element having a surface on one side of its pivot engageable with one inclined surface of the slot to project the blade therefrom upon movement of the member in one direction and another surface on the opposite side of the pivot engageable with the other inclined surface to positively retract the blade into the slot upon movement of the member in the opposite direction.

11. A tool for chamfering and the like comprising an elongated body adapted for insertion through a bore, said body having a slot therein, said slot having a surface inclined with respect to the axis of the body, a member mounted on said body for relative axial movement with respect thereto, a cutter element pivotally mounted on said member and having a blade shielded within the slot, said cutter element having a surface on one side of its pivot engageable with the inclined surface of the slot to project the blade therefrom upon movement of the member in one direction, and spring means acting on said cutter element urging said blade into retracted position.

12. A tool for chamfering and the like comprising, an elongated body adapted for insertion through a bore, said body having a slot therein, a surface of said slot being inclined with respect to the axis of the body, a member mounted on said body for relative axial movement with respect thereto, a cutter element having a blade, a pivotal connection between said cutter element and said member resisting displacement of the cutter element in one direction, spring means yieldingly resisting displacement of the cutter element in the opposite direction, said cutter element having a portion engageable with the inclined surface of the slot to project the blade from within the slot upon relative axial movement between said member and said elongated body.

13. In a tool for chamfering and the like, an elongated body having an axial slot therein, a collar encircling said body and movable axially therewith, said collar also having an axial interior slot, a cutter element within said slots and having a cutting blade, the slot in said collar opening toward said blade, and means connecting said cutter element to said collar for movement axially of said body upon movement of said collar.

14. In a tool for chamfering and the like, an elongated body having an axial slot therein, a collar encircling said body and movable axially with respect thereto, said collar having a slot interiorly thereof, a cutter element in said slots, cooperating abutting surfaces on said cutter and said collar preventing relative axial movement

therebetween, and spring means on said collar acting on said cutter element to normally maintain said abutting surfaces in operative engagement but yieldable in a direction to permit disengagement of said surfaces and removal of said cutter element from the slots.

15. In a tool for chamfering and the like, an elongated body having an axial slot therein, a collar encircling said body and movable axially with respect thereto, said collar having a slot 10 interiorly thereof, a cutter element in said slots, means for releasably connecting said cutter element to said collar for pivotal movement, said means comprising complementary pivot surfaces on said cutter element and the interior of the collar slot and spring means acting on said cutter element to normally maintain said surfaces in operative engagement but yieldable to permit their disengagement and removal of the cutter element from the slots.

16. In a tool for chamfering and the like, an elongated body, a cutter element mounted on said body for movement axially thereof, a collar mounted on said body for movement axially thereof, said collar being non-rotatable relative to said elongated body, means connecting said cutter element to said collar for moving said cutter element in response to movement of said collar, and a sleeve rotatably mounted on said collar.

17. In a tool for chamfering and the like, an elongated body, a cutter element mounted on said body for movement axially thereof, a collar mounted on said body for movement axially thereof, said collar being non-rotatable relative to said elongated body, means connecting said cutter element to said collar for moving said cutter element in response to movement of said collar, and cooperative means on said collar and said elongated body for positively holding said collar in position axially of said elongated member.

18. In a tool for chamfering or the like, an elongated body, a cutter element mounted on

said body for movement axially thereof, a collar mounted on said body for movement axially thereof, means connecting said cutter element to said collar for moving said cutter element in response to movement of said collar, and a spring actuated element in said collar cooperatively engaging a depression in said body for holding said collar in adjusted axial position.

19. A tool for chamfering and the like comprising, an elongated body adapted for insertion through a bore, said body having a slot therein, the ends of the slot having surfaces inclined oppositely with respect to the axis of the body, a member mounted on said body for axial movement with respect thereto, a cutter element mounted in said slot for axial movement of the body and having a blade adapted to be shielded within the slot, means operatively connecting said member and said cutter element, said cutter element having surfaces adjacent its end portions respectively engageable with said inclined surfaces, engagement of one of said surfaces with one of said inclined surfaces, in response to movement of said member in one direction serving to project the blade from the slot, and engagement of the other of said surfaces with the other inclined surface in response to movement of said member in the other direction serving to retract the blade into the slot.

20. A tool for chamfering and the like, comprising a body adapted for insertion through a bore, a cutter element having a blade and mounted on said body for axial movement with respect thereto, and spaced cooperative complementary means respectively on the body and cutter element for projecting the blade in response to relative movement between the cutter element and the body in one direction and for retracting the blade in response to relative movement between 35 the cutter element and the body in the opposite direction.

DON HEYER.
